United States Patent Office.

EDGAR M. STEVENS, OF CHELSEA, MASSACHUSETTS, ASSIGNOR TO ALFRED B. ELY, OF NEWTON, MASSACHUSETTS.

Letters Patent No. 63,573, dated April 2, 1867.

IMPROVED HEEL-STIFFENER.

The Schedule referred to in these Letters Patent and making part of the same.

Be it known that I, EDGAR M. STEVENS, of Chelsea, in the State of Massachusetts, have invented a new and useful Improvement in Rubber Heel-Stiffening, of which the following, with the drawing, is a full description.

In the drawing is represented a heel-stiffener of rubber, made in the usual manner, and moulded in proper form. It differs from all stiffenings heretofore made, in having the upper circular edge rounded over outward, and it is so moulded when made. Heel-stiffeners as heretofore made of rubber had their upper edge rather slanting forward, and in wearing this slant would tend to wear the lining, and for that reason objections have been made to them. To obviate this I have made my invention and improvement. The shoe or boot will go on the foot more easily and the lining will not wear through. This is an improvement on my former inventions in this direction.

What I claim, and desire to secure by Letters Patent, is—

A moulded heel-stiffening of rubber, or similar elastic material, having its upper edge turned over outwardly, as and for the purposes set forth.

In testimony whereof I have hereunto subscribed my name.

E. M. STEVENS.
